(57) **CLAIM**

The ornamental design for an aircraft window, as shown and described.

DESCRIPTION

FIG. 1 is a front and left side perspective view of an interior of an aircraft window;

FIG. 2 is a front elevational view thereof;

FIG. 3 is a front and left side perspective view of an interior of a second embodiment of an aircraft window; and,

FIG. 4 is a front elevational view thereof.

The broken lines in FIGS. 1 through 4 represent the boundaries of the claim and form no part thereof.
